UNITED STATES PATENT OFFICE.

ABNER T. SHEETS, OF BRIDGEWATER, VIRGINIA.

PUMP.

SPECIFICATION forming part of Letters Patent No. 247,696, dated September 27, 1881.

Application filed April 16, 1881. (No model.)

To all whom it may concern:

Be it known that I, ABNER T. SHEETS, a citizen of the United States, resident at Bridgewater, in the county of Rockingham and State 5 of Virginia, have invented certain new and useful Improvements in Pumps; and I do hereby declare the following to be a full, clear, and exact description of the invention, such as will enable others skilled in the art to which it app- 10 pertains to make and use the same, reference being had to the accompanying drawings, and to letters or figures of reference marked thereon, which form a part of this specification.

Figure 1 is a vertical section, Fig. 2 is a de- 15 tail, and Fig. 3 is a detail view of the flattened flaring inlet.

This invention has relation to double-acting pumps; and it consists in the improved fea- 20 tures of construction and combination herein- after fully described, and particularly pointed out in the claim.

Referring by letter to the accompanying drawings, A designates the cylinder, having its upper head, B, provided with the collar C. 25 This collar is internally threaded, and a hollow screw, D, having a transversely-grooved head, through which the piston-rod passes, is seated in this collar, and is longer than the collar, as shown. The lower head of the cyl- 30 inder A is provided with an upwardly-flaring flattened inlet, E, which connects with the suc- tion-pipe, and has a branch pipe, F, extending up outside of the cylinder A and connect- ing with an elbow, G, curved, as shown, at the 35 top of the cylinder and at one side of the same. The bottom of the cylinder is provided with a valve, H, opening upwardly. The upper end of the branch pipe F is provided with a valve, I, also opening upwardly. At the opposite side 40 of the cylinder A, near its lower end, is an el- bow, J, opening into the cylinder, and from this leads a branch or side pipe, K, which forms part of the educt L.

A valve, M, is located at the junction of the 45 elbow J and the branch pipe K. Opposite the elbow G the cylinder A opens into the educt L, and is provided with a valve, N, opening upwardly.

It will be noticed that all the valves in this 50 pump are on a horizontal plane, while hereto-fore in this class of pumps the valves have been suspended vertically, and the result of

such suspension has been that cross-currents of the water have been produced, and the friction of the pump is so great as to cause the 55 pump to work very hard.

In my pump the piston or plunger O is con- 60 structed of two disks, a a', having annular edge flanges b b', bent rearwardly at an angle of about seventy degrees, thereby leaving their back surfaces plane. Between these disks, and on the piston-rod P, are secured two leather washers, c c', the edges of which project about one-fourth of an inch beyond the bent edges of the disks a a'.

The rear faces of the projecting edges of the disks a a' are preferably rounded, to prevent 65 too rapid wear of the leather washers, and in fact this rounding of the rear faces of these projections causes the usefulness of the washers to be maintained for a great length of time. The reason for projecting the washers beyond the disks a a' is to cause the washers to always bear against the walls of the cylinder.

The educt-pipe is provided with the usual 70 air-chamber, Q. R is the handle, pivoted in a standard, S, rising from the educt-pipe, and pivoted also to the upper end of the piston-rod P. A pin, T, is passed through the piston-rod 75 P above the hollow screw D. The object of this pin is to permit the piston-rod P to be em- ployed to tighten the screw, when it has be- 80 come worn by use, by disconnecting the han- dle from its standard, lowering the piston un- til the pin enters the groove in the head of the 85 screw D, and by using the handle as a lever turn and tighten the screw in its seat.

The circumstances under which the screw 90 becomes worn are as follows: The piston-rod passing up and down through the hollow screw jars the same in its seat, and in time the threads in the seat become worn. It is then necessary to drive the screw farther down in its seat, which is done in the manner above described. This is advantageous, for the reason that the 95 cylinder is below the platform U, and to tighten it otherwise would require the removal of one or more boards, and would be even then at- tended with difficulty.

With reference to the cross-currents hereto- 100 fore mentioned, they occur in other pumps, for the reason that in most, if not all, of them, the majority, in fact, nearly all, of the valves are suspended vertically, and the water, in passing

through, is caused to flow or is forced in a horizontal direction, while the object is to get them to the point of discharge as directly as possible and with the least friction and exertion attainable.

Let the cylinder A be filled with water. A downward stroke of the piston will force the water up through the branch pipe K into the educt, and the water from the suction-tube 10 will flow through the branch pipe F and fill the vacuum above the piston. An upward stroke will close the valves I and M and open the other valves. The curves of the pipes and elbows are such that the water has as nearly as 15 possible an upward direction, and no cross-currents are induced, whereby the friction is lessened, and consequently less force is required to operate the pump.

Having thus fully described my invention, what I claim as new, and desire to secure by 20 Letters Patent, is—

In a pump, the combination, with the cylinder A, having the collar provided with the hollow screw grooved in its head, of the piston-rod provided with a transverse pin for entering said groove, substantially as and for the purpose set forth.

In testimony whereof I affix my signature in presence of two witnesses.

A. T. SHEETS.
